THREAD CUTTING DEVICE FOR SEWING MACHINES

Sarkis N. Jafferian, Watertown, Mass.

Application May 10, 1935, Serial No. 20,845

12 Claims. (Cl. 112—252)

My invention relates to sewing machines and has particular reference to thread cutting means for such machines.

An important object of the invention is to provide means for automatically cutting the upper thread, when the presser foot is raised.

A further object of the invention is to provide means for cutting the lower thread, which means is arranged beneath the bed-plate, so that it does not interfere with the usual sewing operation.

A further object of the invention is to provide means to stop the machine when the thread take-up lever and needle are raised, so that the thread will not be withdrawn from the eye of the needle when the machine is again set into operation after the thread is cut, or the machine stopped for other purposes.

A further object of the invention is to provide thread cutting means which will save time, as well as thread, during the sewing operations.

A further object of the invention is to provide means of the above mentioned character which are simple in construction and reliable in operation.

Other objects and advantages of the invention will be apparent during the course of the following description.

In the accompanying drawings forming a part of this application, and in which like numerals are employed to designate like parts throughout the same,

Figure 1 is a side elevation of the conventional type of sewing machine, showing my invention applied thereto,

Figure 2 is an end elevation of the sewing machine, showing my brake mechanism associated therewith,

Figure 2a is a detailed section through the sliding wedge,

Figure 3 is a perspective view of the brake mechanism,

Figure 4 is an end elevation of the machine, showing the thread cutting device associated with the presser foot,

Figure 5 is a perspective view of the thread cutting device secured to the presser foot,

Figure 6 is a similar view of the same, showing the parts separated for the purpose of clearness,

Figure 6a is a side elevation of the upper thread cutting device,

Figure 7 is a plan view of the device for cutting the thread from the shuttle,

Figure 11 is a plan view of a blade included in a modified form of lower thread cutting device,

Figure 12 is a plan view of the lower thread cutting device,

Figure 13 is a diagrammatic view showing the association of the lower thread cutting device, needle and shuttle, before the thread cutting device is actuated, and,

Figure 14 is a similar view showing the lower thread cutting device actuated.

In the drawings, wherein for the purpose of illustration is shown a preferred embodiment of my invention, the numeral 15 designates a sewing machine as a whole, which may be of any conventional type, such as the ordinary "Singer" sewing machine, used in sewing garments. This sewing machine comprises a stock 16, arms 17, and head 18. The stock is mounted upon the usual flat base or table 19, supported in any suitable manner. The head 18 carries a vertical reciprocating needle bar 20, to which is attached the needle 21, having an eye 22 for receiving the thread 23. This thread is passed upwardly

through the eye 24 of a vertically movable thread take-up lever 25, and then beneath the lever 26, which, in the present instance, is held stationary by a headed screw 27. The thread then passes through a thread tension device 28 and through guides 29 and 30, and to the spool 31, from which it is unwound. The sewing machine embodies the usual means to reciprocate the needle bar 20 and raise and lower the thread take-up lever 25. This means includes a wheel 32, having a grooved pulley 33 for receiving a belt, not shown, employed in driving the wheel 32.

This belt may be manually operated or power driven, as is well known. Coacting with the needle 21 is the usual presser foot 34, secured to the lower end of a reciprocating presser bar 35, in turn slidably mounted upon the head 18.

The presser foot has the usual needle receiving passage, as shown. The presser bar 35 may be raised by swinging a lever 36 upwardly, or the presser bar may be raised by swinging a knee engaging element or treadle 37 laterally. Co-

operating with the needle 21, for producing the stitch, is an oscillating shuttle 38, operating in a shuttle race-way 38' arranged beneath the bed 19. The lower thread from the bobbin passes

through an opening 39', in the race-way 38'. The shuttle 38 is caused to oscillate by a suitable mechanism, not shown, which is actuated by the reciprocating motion of the needle bar 20.

Figure 1 illustrates the conventional type of sewing machine, showing the stock 16, arms 17, head 18, needle bar 20, needle 21, eye 22, thread 23, spool 31, wheel 32, pulley 33, belt 34, presser foot 35, treadle 37, lever 36, lever 25, lever 26, screw 27, guides 29 and 30, and base 19.

Figure 2 illustrates the end elevation of the machine, showing the stock 16, arms 17, head 18, needle bar 20, needle 21, eye 22, thread 23, spool 31, wheel 32, pulley 33, belt 34, presser foot 35, treadle 37, lever 36, lever 25, lever 26, screw 27, guides 29 and 30, and base 19.

Figure 3 illustrates a perspective view of the brake mechanism, showing the stock 16, arms 17, head 18, needle bar 20, needle 21, eye 22, thread 23, spool 31, wheel 32, pulley 33, belt 34, presser foot 35, treadle 37, lever 36, lever 25, lever 26, screw 27, guides 29 and 30, and base 19.

Figure 4 illustrates an end elevation of the machine, showing the stock 16, arms 17, head 18, needle bar 20, needle 21, eye 22, thread 23, spool 31, wheel 32, pulley 33, belt 34, presser foot 35, treadle 37, lever 36, lever 25, lever 26, screw 27, guides 29 and 30, and base 19.

The usual means are provided to feed the work from the operator as the stitch is formed. The foregoing description is that of the ordinary or conventional sewing machine. The conventional sewing machine includes upper and lower thread stitch forming mechanism which has been shown and described generally. Such mechanism may be of the type shown in Patent 1,877,757 or 1,051,998, but the invention is not restricted to any particular type of stitch forming mechanism.

One thread cutting device is mounted upon the presser foot 34, Figures 1, 4, 5, 6 and 6a. It is arranged upon that end of the presser foot 15 remote from the operator. This thread cutting device includes a block 39, having apertures 40, for receiving screws or bolts 41 and 42, which also pass through apertures 43, formed in the shank 44 of the presser foot. The block 39 has a 20 thread guiding opening, groove, or recess 45, passing through its lower end, and adapted to register with the slot or opening 46 of the presser foot. This thread guiding means extends longitudinally of the direction of the feeding of the work. 25 The thread guiding grooves or passages 45 and 46 form one continuous passage leading into the needle receiving passage of the presser foot and extending to the exterior thereof. A stationary blade 47 has apertures 48 for receiving the screws 30 or bolts 41 and 42. The cutting edge 49 of this blade is arranged adjacent to one side of the thread guiding opening or recess 45, as shown. Coacting with the stationary blade 47 is a swinging blade 50, having an extension 51, apertured 35 for pivotally receiving the upper bolt 41. The blade 50 has a curved presser-extension 52, slidably engaging beneath the head of the lower bolt 42, this lower bolt carrying a spacing washer 53, next to the head 42. The function of the presser- 40 extension 52 is to retain the cutting edge 54 of the blade 50 close to the cutting edge 49 of the stationary blade, thus producing a proper shearing or cutting action of the thread, when the blade 50 is swung downwardly upon its pivot 41. 45 Pivotally connected with the outer end of the blade 50, at 55, is a link 56 extending upwardly for pivotal connection at 57, with a bracket 58, and this bracket is rigidly attached to the lower end of the head 18 by screws 59, or the like. The head 18 being stationary when the presser foot is raised, the blade 50, having its extension 51 raised while its end attached to the link 56 is held at the same elevation, such blade 50 is swung upon its pivot 55, and the cutting edge 54 of the 55 blade is moved toward the cutting edge 49. It might be stated at this point that the distance that the cutting edge 54 is spaced from the cutting edge 49, when the presser foot 34 is in the lower-most position, is such that the cutting edge 54 will not be brought into cutting relation or engagement with the cutting edge 49, upon any slight or partial raising movement of the presser foot, but the presser foot must be moved upwardly to the end of its travel before the blade 60 50 is turned sufficiently to cause the cutting edge 65 54 to coact with the cutting edge 49, to cut the thread between these edges. This is important as the presser foot is positioned at different elevations when working upon cloth of different thicknesses, and the cutting device will not cut the thread until the presser foot has been moved to the uppermost position. The presser-extension 52 remains permanently under the head of the bolt 42. It might be stated at this point that 70 75 when the line of stitching 57, formed in the

work or garment 58, is produced and it is desired to cut the thread 23 of the needle 21, the presser foot is raised and at the beginning of the upward movement of the presser foot the work is shifted from the operator and this pulls the thread into the thread guiding opening 45 and between the cutting edges 49 and 54, and when the presser foot is raised to the uppermost position, these cutting edges will then cut the thread arranged between them.

A device is also provided to cut the lower thread from the oscillating shuttle, and this thread is indicated by the numeral 59, Figures 7 and 10. The bed 19 is provided with an opening 60, having an end wall 61, Figures 7, 8, and 10. This opening is covered by the usual removable plates 60', whereby the rotary shuttle 38 and associated elements are covered. Arranged within the opening 60, upon one side of the rotary shuttle 38, is a stationary bearing 62, held in place by a bolt 20 or bolts 63, engaging the base 19. This bearing is at an elevation beneath the base 19, or cover plates carried thereby, and this bearing receives and holds a vertical rock shaft 64, also journalled near its lower end in a bearing 65, formed in an 25 arm 66, which is bolted or otherwise rigidly attached to a stationary lug 67, as shown at 68. A tortional coil spring 69 surrounds the rock shaft 64 and has one end attached to the same, while the opposite end of this spring is attached 30 to the arm 66, as shown. This spring is tensioned to turn the rock shaft 64 counter-clockwise in the direction of the arrow, Figure 8, for a purpose 35 to be described. Connected with the lower end of the rock shaft 64 is a sprocket wheel 70 engaged by a sprocket chain 71, engaging a sprocket wheel 72 rigidly mounted upon a vertical shaft 73. This vertical shaft is journalled in bearings 74 carried by a bracket 75, and this bracket is rigidly attached to the table top 76 or other suitable support. The shaft 73 is turned by means of a lever 77, rigidly attached thereto and this lever has a depending extension 78, in the form of a treadle or knee pressing element so that the lever 77 may be swung outwardly to the left by 40 the left knee. When this is done, the shaft 73 is turned and this turning movement is transmitted to the rock shaft 64, which will then be turned clockwise in an opposite direction to the arrow, 45 Figure 8, to actuate the thread cutting device 50 carried thereby. This thread cutting mechanism comprises a lower plate or blade 79, provided at one end with a head 80, having openings 81, formed therein for receiving screws 82 or the like, which engage within screw-threaded openings 83, formed in the top of the rock shaft 64. The plate or blade 79 is therefore rigidly attached to the upper end of the rock shaft to be turned in a horizontal plane thereby and this plate or blade operates above the oscillating shuttle 38, and 55 beneath the cover plate or plates 60' and in no way interferes with the operation of the shuttle 38 and associated elements. The lower plate or blade 79 has its free end opposite the head 80 provided with a V-shaped recess 84, affording sharp thread cutting edges 85. These edges converge in one direction to a point 86, at which the lower thread 59 is cut. Arranged upon the lower plate or blade 79 is a guard plate 87, and these plates are pivotally connected by a screw 88 or the like. The guard plate has its free end 89 normally covering the inner portions of the converging edges 85 and point 86. The guard plate 87 has a stop extension or finger 90, bent downwardly to enter a recess 91 in the lower plate 79 70 75

and to engage the end wall 92, to limit the covering movement of the guard plate 87. This guard plate is swung to the covering position with respect to the lower plate 79 by means of a compressible coil spring 93, receiving extension 94 of the guard plate 87 and the extension 95 of the lower plate 79 and having its outer end attached to the extension 95 by winding the same within notches 96 or the like. The guard plate 87 also has a shifting extension 97 extending laterally beyond the same for a substantial distance and also laterally beyond the lower plate 79, as shown. The shifting extension 97 is adapted to engage the end wall 61, as will be explained. When the rock shaft 64 is in the normal or starting position, the lower plate 79 is shifted to the left, the end 89 of the guard plate 87 covers the cutting point 86 of the cutting edges 85, and shifting extension 97 is spaced from wall 61. When the rock shaft 64 is turned clockwise, the shifting extension 97 is brought into engagement with the wall 61 and stops the swinging movement of the guard plate 87, while the lower plate 79 continues to move until end 98 contacts with the wall 61. There is therefore a relative swinging movement between the guard plate 87 and the lower plate 79 with the result that end 89 uncovers the cutting point 86 of the edges 85. The thread 59 from the shuttle during the sewing operation, is guided or passes between the blades 85, but does not contact therewith, and since end 89 covers the cutting point 86, the thread 59 is not cut. The needle also operates between the cutting edges 85 and the needle and its thread do not touch the cutting edges 85. Now when the cutting device, including the plate 79, is shifted to the right, Figure 10, the cutting point 86 is uncovered, and the thread 59 extending from the shuttle to the line of stitching, beneath the cloth, engages the cutting edges 85 at the point 86, and since this thread 59, beneath the cloth, is pulled laterally from the shuttle by the cutting device, such thread will be automatically cut by the device, without the necessity of the operator moving the cloth away from him, as was done with cutting the upper thread from the needle. This lower thread 59 is held at its top by the cloth and at the bottom by the shuttle and hence is cut between these two points.

In Figure 11, I have shown a modified form of cutter. This cutter comprises the same blade 79, having a recess 100 and cutting edge 85. This blade 79 is mounted upon the rock shaft 64 and is turned thereby. Arranged upon the lower blade 79 is an upper blade 102, pivoted thereto at 103, and this upper blade has a cutting edge 104 opposed to the cutting edge 85. A shifting extension 106 is provided to engage the wall 61 and the same spring arrangement is provided to normally hold the cutting edge 104 spaced from the cutting edge 85. The needle and the two threads normally operate between these cutting edges and have no engagement therewith, but when the cutting device is shifted to the right, the blade 102 is swung upon its pivot 103 and blade 104 closes upon blade 85, and cuts the thread beneath the cloth, which is attached at its top to the cloth and at its bottom to the shuttle.

Brake mechanism is provided to stop the operation of the sewing machine, when the thread take-up lever 25 is in the uppermost position, so that this thread take-up lever cannot pull the thread from out of the eye of the needle when the machine is again started. This brake mech-

anism comprises a stop lug 107 rigidly secured to the periphery of the wheel 32 by a bolt 108 or the like. The stop lug 107 is provided with a cushion 109, formed of resilient material, such as rubber, and held in place by a socket 110, 5 carried by the stop lug. Arranged opposite the stop lug 107 is a rebound-stop element 111 having sides 112, slidably mounted in radial grooves 113, formed in the end faces of the rim of the wheel 32. The inner ends of the sides 112 are preferably bent inwardly slightly and are connected by a transverse element or bolt 114. The rebound stop element 111 is radially movable with relation to the wheel 32 and the stop element is normally projected radially outwardly by a compressible coil spring 115. The outer end of the rebound stop element is beveled, as shown at 116. The transverse element or bolt 114 has connection with a retractile coil spring 117, attached to a pin 118, secured to the wheel 32. The spring 20 117 serves to normally tilt the stop element 111 upon its transverse axis, as shown.

Arranged near and beneath the wheel 32 is a vertical tubular guide 119, formed integral with a stationary base 120, bolted or otherwise rigidly 25 attached to the table top 16, as shown at 121. Mounted to slide within the vertical tubular guide 119 is a bolt 122, the upper end of which is beveled, as shown at 123. The beveled faces 123 and 116 are inclined in the same direction, as shown. 30 The bolt 122 is projected above the tubular housing 119 by means of a horizontal sliding wedge 124, operating in a transverse recess 125. The upper face of the wedge 124 is inclined and has a longitudinally extending passage 126 and a slot 35 127 above the same. A head 128 is slidable within the passage 126 and has a shank 129, operating in the slot 127 and rigidly secured to the lower end of the bolt 122. It is thus seen that the sliding wedge 124 will raise or lower the bolt 122, 40 depending upon the direction in which it is moved. Bolts 128 engage in grooves 129' and hold element 124 in place. The wedge 124 carries a pin or bolt 130, operating within curved slots 131 formed in a vertically swinging lever 132 pivoted 45 at 133, and swung in one direction by means of a retractile coil spring 134. This lever is swung in an opposite direction to advance the wedge 124 by the downward pull upon a chain 135, which may extend to a treadle on the floor. Any other 50 suitable means may be employed to swing the lever 132 for stopping the machine. It is thus seen that when it is desired to stop the machine, the treadle is depressed and the lever 132 turned on its pivot so that its upper end is swung toward the tubular housing 119 and the bolt 122 is projected above this tubular housing. At the same time the current is cut off from the motor by any suitable means. The wheel 32 continues to rotate in the direction of its arrow, Figure 2, and beveled face 116 will trip over beveled face 123 and the upper end of the bolt 122 will now engage the shock absorbing block 109 of the stop lug 107. This stop lug engages the side of the bolt and not the beveled face 123 thereof so that the rotation of the wheel in the direction of the arrow is stopped. The rebound stop element 111 being now located in advance of the projected bolt 122 will prevent rotation of the wheel 32 in a reverse direction. The stop lug 107 is so located upon the wheel 32 that the wheel will be stopped by the projected bolt 122 when the thread take-up lever 25 is in the raised position and also when the needle 21 is partly raised and assumes a position slightly above the presser foot. This withdraws 55 60 65 70 75

the needle from the presence of the lower thread cutting device. Since the machine is stopped with the thread take-up lever 25 in the uppermost position, when the machine is again started, the lever 25 makes its down stroke and hence cannot pull the thread out of the eye of the needle 21, when sewing is continued.

The operation of the invention is as follows:

The work 58 is placed upon the base 19, beneath the presser foot 34, in the usual manner, and the presser foot is then lowered to engage the work. The machine is started and the needle and the oscillating shuttle are driven to form the usual line of stitching 57. The thread 23 from the needle 21 extends to the line of stitching 57 on top of the cloth 58, while the thread 59 from the shuttle extends from the shuttle to the stitching 57 beneath the cloth. When the required length of stitching 57 has been made, the lever 137 is shifted to project the bolt 122 and the current is cut off from the motor driving the machine and the machine is stopped, with the thread take-up lever 25 in the uppermost position and the needle 21 elevated to a point slightly above the presser foot, and this presser foot is now in the lowermost position. It is preferred to first cut the top thread 23 from the needle. To do this, the operator raises the presser foot 34 upwardly through a part of its vertical travel, by pressing against treadle 37 or by raising lever 36, and then moves the work 58 away from him, and this causes the thread 23 to enter the opening or recess 45 and pass between the cutting edges 49 and 54, and when the thread is in this position, it has been pulled to a certain extent through the needle. This having been done, the upward movement of the presser foot is continued and when the presser foot approaches or reaches its uppermost position, blade 50 will swing sufficiently upon its pivot 40 to cause cutting edge 54 to close on cutting edge 49 and cut the top thread 23, and this cutting occurs at a point suitably spaced from the eye of the needle so that there is sufficient thread left whereby there is no tendency for the thread to pull out of the eye of the needle when sewing is resumed, lever 25 starting on its down stroke when sewing is again started. The top thread being thus cut, the operator next cuts the bottom or shuttle thread 59, which is effected by swinging the treadle 18 outwardly to the left. The plate 79 of the cutting device now swings to the right from the position shown in Figure 7, to the position shown in Figure 10. When the shifting extension 97 engages the wall 61, guard plate 87 uncovers cutting point 86, and hence the intermediate portion of the thread 59 is now shifted laterally, the top of the thread being attached to the bottom of the work 58 and the lower end of the thread to the shuttle, and the thread is under tension and will be cut at the point 86. Particular attention is called to the fact that the point of cutting is remote from the shuttle so that there is a suitable length of thread extending from the shuttle to provide for the starting of the sewing. An advantage in cutting the lower thread last, is that when the lower thread is pulled prior to cutting, it will draw the cut top thread through the fabric to the lower face of the same. Of course, if desired, the bottom thread could be cut first. The operation of the second form of the lower thread cutting device is very similar to the first form, the cutting being effected by blade 104 closing on blade 85. The movable blade is shifted by its extension engaging the wall 61, as is obvious.

A great saving of time will be effected by the use of my invention. I have found approximately ten seconds can be saved each time, by the use of my invention in the cutting of the thread, over the old method of cutting the same with scissors or by hand. This saving is not only effected by the quick cutting of the thread, but by the fact that the machine is stopped in the right position and it is unnecessary to turn the wheel for adjusting the needle prior to raising the presser foot, and further, it is not necessary to hold the end of the upper thread when starting to sew, as is customary, since the thread take-up lever 25 will start on its down stroke. In accordance with my invention, when sewing is again started, the presser foot is lowered, but it is unnecessary to touch the upper thread. The stopping of the machine when the thread take-up lever is in the uppermost position, is important, even when the thread is cut by hand, as it will permit the starting of sewing without holding the upper thread, or turning the wheel to raise the needle.

The cutting devices are shown as applied to a sewing machine for working on garments or the like, but the invention is in no sense restricted to this type of sewing machine, as the cutting devices may be used in connection with various types of sewing machines. Further, I contemplate using the brake device without the upper and lower thread cutting devices, or with either of such devices, or both of them.

It is to be understood that the forms of my invention herewith shown and described, are to be taken as preferred examples of the same, and that various changes in the shape, size, and arrangement of parts may be resorted to without departing from the spirit of my invention or the scope of the subjoined claims.

Having thus described my invention, I claim:

1. In a sewing machine, a presser foot having a thread guiding passage, a thread cutting device mounted upon the presser foot and including a movable blade to be shifted across the passage to cut the thread, and a link held against longitudinal movement and connected with the movable blade to actuate the blade when the presser foot is raised.

2. In a sewing machine, a presser foot having a needle receiving passage and a thread guiding means, the thread guiding means leading into the needle receiving passage and extending to the exterior of the needle receiving passage, a thread cutting device mounted upon the presser foot adjacent to the guiding means and including a stationary blade and a pivoted blade, a pressure extension carried by the pivoted blade, an element to engage the pressure extension and act upon it so that the pivoted blade is held in close relation to the stationary blade, and means to swing the pivoted blade upon its pivot.

3. In a sewing machine, a presser foot, a thread cutting device mounted upon the presser foot at the end of the presser foot remote from the operator, said thread cutting device having thread guiding means extending longitudinally of the feeding movement of the work, and means to actuate the thread cutting device.

4. In a sewing machine, a presser foot, a thread cutting device mounted upon the presser foot at the end of the presser foot remote from the operator, said thread cutting device having thread guiding means associated therewith, the guiding means being open at its bottom and extending longitudinally of the direction of feeding movement of the work, and means to automatically

- actuate the thread cutting device when the presser foot is raised.
5. In a sewing machine, a presser foot, a thread cutting device mounted on that end of the presser foot remote from the operator, means forming a thread guide leading to the thread cutting device and extending longitudinally of the feeding movement of the work, and means to actuate the thread cutting device.
- 10 6. In a sewing machine, a presser foot having a needle receiving passage and a thread guiding passage, the thread guiding passage leading into the needle receiving passage and extending to the exterior of the needle receiving passage, a thread cutting device mounted upon the presser foot and arranged adjacent to the thread guiding passage to cut the thread within the thread guiding passage, and means to actuate the thread cutting device.
- 15 7. In a sewing machine, a presser foot having a needle receiving passage and a thread guiding passage, the thread guiding passage leading into the needle receiving passage and extending to the exterior of the needle receiving passage, a stationary blade carried by the presser foot adjacent to the thread guiding passage, a pivoted blade mounted upon the presser foot and coacting with the stationary blade to cut the thread in the thread guiding passage, and means to swing the
- 20 8. In a sewing machine, a presser foot having a needle receiving passage and a thread guiding groove which leads into the needle receiving passage and extends to the exterior thereof, the thread guiding groove having its open side arranged lowermost, and a thread cutting device connected with the presser foot to move therewith and disposed adjacent to the thread guiding groove.
- 25 9. In a sewing machine, a presser foot to be raised and lowered, a thread cutting device mounted upon the presser foot and including a
- pivoted blade, and a link held against longitudinal movement and pivotally connected with the pivoted blade to actuate the same when the presser foot is raised.
10. In a sewing machine, a needle, a presser foot having a needle receiving passage and a thread guiding passage, the thread guiding passage leading into the needle receiving passage and extending to the exterior of the needle receiving passage, a thread take-up lever, a thread cutting device mounted upon the presser foot and arranged adjacent to the thread guiding passage to cut the thread therein, means to actuate the thread cutting device, and means to stop the machine with the thread take-up lever and the needle raised so that the thread will not be pulled from the eye of the needle when the needle again descends as the thread take-up lever will move down with it.
- 15 11. In a sewing machine, a needle, a thread take-up lever, a presser foot having a needle receiving passage and a thread guiding passage, the thread guiding passage leading into the needle receiving passage and extending to the exterior of the needle receiving passage, a thread cutting device mounted upon the presser foot and arranged adjacent to the thread guiding passage to cut the thread therein, means to stop the machine with the thread take-up lever and the needle raised so that the thread will not pull from the point of the needle when the needle again descends as the thread take-up lever will move down with it, and means to automatically actuate the thread cutting means when the presser foot is raised.
- 20 12. In a sewing machine, a presser foot, a thread cutting device connected with the presser foot to be bodily shifted thereby, and a link held against longitudinal movement and connected with the thread cutting device to actuate the same when the presser foot is raised.

SARKIS N. JAFFERIAN.
